UNITED STATES PATENT OFFICE.

GEORGE G. FRYER, OF SYRACUSE, NEW YORK.

SAFETY-SEAL FOR RECEPTACLES.

1,157,685.

Specification of Letters Patent. Patented Oct. 26, 1915.

Application filed December 5, 1910. Serial No. 595,640.

To all whom it may concern:

Be it known that I, GEORGE G. FRYER, of Syracuse, in the county of Onondaga and State of New York, have invented a certain 5 new and useful Safety-Seal for Receptacles, of which the following is a specification.

This invention has for its object the production of a safety seal for receptacles containing highly volatile liquids, as aqua ammonia and hydro-carbons; and it consists 10 in the combinations and constructions hereinafter set forth and claimed.

In describing this invention reference is had to the accompanying drawing in which 15 like characters designate corresponding parts in all the views.

Figure 1 is a vertical sectional view of one embodiment of my invention. Fig. 2 is a fragmentary view of the cap shown in 20 Fig. 1.

1 is the receptacle for volatile liquids, such receptacle having an opening 2 in its upper side which is closed by a suitable cover in the form of a dome 3, the cover having an exhaust passage 4. The receptacle may be the ordinary tank car, or any other suitable container; and the exhaust passage 4, although here shown as formed in the cover 3, may be provided at any other convenient part of the 30 receptacle.

5 is the safety seal extending across the exhaust passage 4, this seal being usually an imperforate diaphragm usually formed of metal, as lead, and being strong enough to 35 withstand a predetermined pressure from within the tank, and to rupture if the pressure increases above the predetermined amount.

6 is a cap mounted on the upper end of the 40 cover 3, or walls of the passage 4 thereof, the cap having openings in its side walls and the openings being arranged at inclined angles relatively to the axis of the passage 4 for directing the gases projected through the 45 openings after the diaphragm 5 is ruptured.

As here illustrated the cap 6 is provided with downwardly and outwardly inclined openings 7, and the jets expelled through such openings are deflected upwardly by an 50 annular deflector 8 extending around the base of the cap, and here shown as formed integral with the cap. Owing to the angle of the openings 7 and to the deflector 8, the gases shoot upwardly in a column instead 55 of flashing in all directions. Thus injuring

of persons and damaging of property near the receptacle, is avoided.

The cap serves as a guard for the diaphragm and the inclined openings 7 also prevent the insertion of sticks into the cap 60 for the purpose of maliciously rupturing the diaphragm.

The cap is held in position by clamping members as bolts 9 extending through the bottom of the deflector 8 and through a 65 flange 10 projecting from the cover 3 near the upper edge of the walls of the passage 4, and usually the diaphragm 5 is clamped between such cap and the upper edges of the walls of the passage 4. Preferably as seen 70 in Fig. 2, the cap is formed with a duct 11 near its base through which water or other liquid on the diaphragm 5 may drain off, the duct 11 also opening through the bottom 75 of the deflector 8.

Owing to my safety seal for receptacles, leakage of gases, and consequently weakening of the liquids in such receptacles is prevented by the diaphragm and the strength or thickness that the diaphragm must be 80 made in order to withstand a given pressure, can be accurately determined, and thus my safety seal is of advantage over the ordinary safety valve heretofore employed as there is 85 always leakage of the valve, and it cannot 85 be determined with any degree of accuracy at what point the safety valve must be set in order to be released when a certain internal pressure is reached.

What I claim is:

1. A receptacle for volatile liquids having an exhaust passage, a safety seal extending across the exhaust passage, a cap for the exhaust passage having escape openings which are inclined downwardly and outwardly, the cap being formed with a deflector in the form of an upwardly facing gutter arranged in the path of the jets projected through said escape openings, and means for clamping the cap in position, substantially as and 100 for the purpose described.

2. A receptacle for volatile liquids having an exhaust passage, a safety seal comprising a diaphragm extending across the exhaust passage and resting on the upper edge of the 105 wall forming the exhaust passage, a cap mounted above the seal and resting on the margin of the seal, the cap having escape openings which are inclined downwardly and outwardly, and the cap being formed at 110

its lower margin with a deflector in the form of an upwardly facing gutter arranged in the path of jets projected through said escape openings, the cap being formed with a drain opening extending into the interior thereof and also opening through the bottom of the gutter flange, and means for clamping the cap in position without turning the same, substantially as and for the purpose described.

3. A receptacle for volatile liquids having an exhaust passage, a safety seal extending across the exhaust passage, a cap for the exhaust passage having escape openings which are inclined downwardly and outwardly, the cap being formed with a deflector in the form of an upwardly facing gutter arranged

in the path of the jets projected through said escape openings, the exhaust passage having a laterally extending flange opposed to the lower side of the gutter, and fastening members extending through the bottom of the gutter and the flange, substantially as and for the purpose set forth.

In testimony whereof, I have hereunto signed my name in the presence of two attesting witnesses, at Syracuse, in the county of Onondaga, in the State of New York, this 17th day of November 1910.

GEORGE G. FRYER.
